UNITED STATES PATENT OFFICE.

JOHN J. DUFFIE, OF BERKELEY, CALIFORNIA, ASSIGNOR TO GOVERNMENT OF THE UNITED STATES.

THERMOMICROPHONIC FIRING DEVICE FOR SUBMERGED MINES.

Application filed August 9, 1917. Serial No. 185,245.

To all whom it may concern:

Be it known that I, JOHN J. DUFFIE, a citizen of the United States, residing at Berkeley, in the county of Alameda and 5 State of California, have invented certain new and useful Improvements in Thermo-microphonic Firing Devices for Submerged Mines, of which the following is a specification.

10 This invention relates to a thermo-microphonic firing device for submerged mines.

The primary object of this invention is to create the explosion of a submerged mine through the medium of the sound waves 15 emanating from a submarine or other vessel in the vicinity of the mine.

An explosive mine when positioned in the sea presents a small target to be struck by a submarine. In fact, a field of mines thickly anchored often fails to provide an effective barrier for enemy vessels. "Destructive nets" and cable barriers are placed in position under great difficulty, they always require considerable time for adjustment, 25 and their points of location are easily discovered by the enemy.

Through the use of my firing device, the foregoing objections or difficulties are overcome. First, for the reason that I create 30 a danger field or zone of a given diameter radiating from the mine. Second, for the reason that by placing a series of thermo-microphonic operated mines at certain distances apart so that the danger fields or 35 zones are contiguous or slightly interlap, thereby creating an absolute barrier against the passage of enemy vessels.

My thermo-microphonic system of firing mines is to be adjusted previously to "setting the mine", so that no extra time is consumed when placing the mine in an operative position. Further, by using the timing device shown in my pending application, 40 filed July 24, 1917, Serial No. 182,481, in operative conjunction with my present firing device, the former will positively prevent the vibrations from the "planting ship" from creating an explosion of the mine during any predetermined or prescribed length of time.

With the foregoing and other objects in view that will appear as the nature of the invention is better understood the same consists in the novel features of construction, 45 combination and arrangement of parts il-

lustrated in the drawings and more particularly pointed out in the appended claims.

In the accompanying drawings, in which like parts are designated by like characters throughout the several views,

60 Figure 1 is a detail fragmentary sectional view of a submerged mine illustrating the application of my thermo-microphonic firing device;

Figure 2 is a diagrammatic view of the 65 firing device;

Figure 3 is a detail central longitudinal section of the microphonic receiver;

Figure 4 is a vertical transverse section 70 taken on the line 4-4 of Figure 3, looking in the direction indicated by the arrows;

Figure 5 is an elevation of the circuit closer with the mercurial container and associated parts shown in section, and

Figure 6 is an edge view of the circuit 75 closer looking at right angles to Figure 5.

Referring to the drawings for a more particular description of the invention, and which drawings are for illustrative purposes only and are, therefore, not drawn to 80 scale, 1 indicates a mine, 2 the microphonic receiver, 3 the circuit closer, 4 the solenoid magnet which projects the firing pin, 5 the firing pin and 6 the detonating cap of the mine. The mine may be provided with a 85 hollow compartment or space 7 at the top, in which may be arranged the firing apparatus.

The microphonic receiver 2 of the firing 90 device may be supported in operative position on or in the mine, in any suitable manner. For example, a hollow cylindrical interiorly threaded supporting member 9 may be bolted, as at 10, to the top wall 11 of the mine shell or casing with its inner 95 end projecting into the compartment or space 7 and the cylindrical body member, as 12, of the microphonic receiver 2, exteriorly threaded, as at 13, for screw-threaded engagement with said member 9. As shown 100 in Figure 1, the inner end of the body member 12 of the microphonic receiver may project somewhat beyond the adjacent or corresponding end of the supporting member 9, to provide for the application of 105 the washer and lock nut 14 and 15, respectively, whereby said body member 12 may be securely held in place. However, in actual practice any other suitable or equivalent means may be utilized to support the 110

microphonic receiver in position on the mine.

The circuit closer 3 which is situated in the compartment or space 7 at the top of the mine, adjacent the microphonic receiver, is mounted on the upright approximately rectangular oblong base 16. Specifically, the circuit closer comprises a hollow cylindrical mercurial container 17, gradually tapered at both ends and supported in a vertical position on the base by the keeper rings 18 and 19 of the bearing brackets 20, fastened by screws 21 or other equivalent means to the base 16. The upper end of the mercurial container is provided with a hollow stem 22 of reduced diameter, the upper end of which is received by the packing gland 23 to provide a close fitting joint and cushion for said end of the stem. An electrode 24 extends into the upper end of the stem 22 of the mercurial container and is carried by an insulated arm 25 extending laterally or at right angles from the upper end of the supporting bar 26. Said electrode may be adjusted in a vertical plane either up or down by means of the aforesaid bar 26, which is slidably mounted in the bearing lugs or brackets 27 of the base, and is retained in adjusted position by the screw 28 or other equivalent means.

A resistance coil 29 closely surrounds or encircles the body portion of the mercurial container 17, the lower end or bottom of which is electrically connected with one side of the battery 30 by the conductor 31. The upper end or top of the resistance coil is connected with a second conductor 32, which cooperates with other parts hereinafter described, in closing the circuit to the other side of the battery, when the sound waves generated by an approaching submarine or other enemy vessel within the field or area of influence on the microphonic diaphragm are transmitted through the medium of the water to the diaphragm 33 of the microphonic receiver. The diaphragm 33, which in the present illustration is in the form of a relatively thin disc, and is arranged in the outer end of the cylindrical body member 12 of the microphonic receiver, is insulated from said body member 12 by the insulating ring 34, and is provided at the center with a horizontal inwardly extending arm 35 to which is connected an oscillating or vibratory arm 36, the upper end of which works between and is adapted to alternately engage or contact with flanges 37 formed at opposite ends of a spool 38, equipped with a threaded stem 39, which passes through a corresponding transverse opening in the cross bar 40 and is held in place by the fastening nut 41. As shown, the inner end of the stem 39 of the spool 38 is connected, as at *a*, with the conductor 32. It will also be noted that the lower end of the oscillating

arm 36 is pivoted to the bearing post 43 secured to and insulated from the cross bar 40 by a screw threaded insulating plug 44.

In practice, when a submarine or other enemy vessel comes within the circle or area of influence upon the microphonic diaphragm 33, the sound vibrations generated by and emanating from said vessel are transmitted through the medium of the water to and are "picked up" by the diaphragm 33 of the microphonic receiver which creates a vibratory action of the diaphragm, which, in turn, imparts an oscillating or vibratory movement to the arm 36, the upper or free end of which alternately contacts with the flanges 37 of the spool 38, as before stated. Under these conditions, as the submarine gradually approaches the mine, the electrical pulsations from the battery 30 to the resistance coil 29 gradually raise the temperature of the mercury in the thermostatic container 17, thereby causing it to expand and slowly ascend in the stem 22 of said container until it reaches and comes into contact with the lower end of the electrode 24. The circuit from the battery 42 through the solenoid magnet 4 is then closed, thereby causing the firing pin 5 to strike or impact the detonating cap 6 and create an explosion of the mine. The mercury in the container 17 is placed in electrical circuit with one side of the battery by the conductor 45. The electrode 24 is connected with the solenoid magnet 4 by the conductor 46, and the solenoid magnet is connected with the other side of the battery by the conductor 47. The outer end of the microphonic receiver is preferably closed by the closure cap 48.

If desired, the microphone may be of any type other than that illustrated, such, for instance, as the vibratory metal ring type, etc. Also, if desired, the diaphragm of the microphonic receiver may be tuned in harmonic accord with the dominant tone created by the submarine motor.

A graduated indicator 50 is adjustably mounted on the base 16 to compensate for the varying temperatures in the different seas or other bodies of water in which the mines may be placed. The lower end of the plate 50 is adjusted to the top of the mercury column in the tube 22, the height of said column of course varying with the temperature of the water in which the mine is immersed. The electrode 24 is then adjusted with reference to the scale, to leave between its lower end and the top of the mercury column the number of spaces or graduations through which said column will expand under a given rise of temperature. In this way the time required to establish electrical connection through the mercury and through coil 4, battery 42 and intermediate conductors, can be accurately determined. These adjustments are made with reference to the

average speed of submarines, and with a view to allowing time sufficient for the craft after entering the zone of receptivity of the microphone to approach within the area of 5 destructivity of the mine.

From the foregoing description taken in connection with the drawings, it is thought that the construction, operation and advantages of this invention will be readily understood without requiring a more extended explanation. Various changes in the form, proportions and minor details of construction may be resorted to without departing from the principles or sacrificing any of the 10 advantages of this invention as defined in the appended claims.

I am aware that it has been proposed to effect the transmission of signals, and to operate or control electrical devices at a distance, by transmitting from a distant station on land or afloat, predetermined sound-waves to act upon a microphonic device at the distant point, through which the signals are given or the electrical devices are 15 brought into action. I am further aware that a thermostatic circuit closer is not broadly a new device. So far as I am aware, however, no one has ever before produced or proposed a mine of the submerged class 20 which should be automatically detonated or exploded by devices brought into action through sound-waves emanating from a vessel entering a predetermined zone about the mine. While various of the elements employed by me are old per se, the structure described and the application of the elements recited are believed to be new, and they produce a result not heretofore attained 25 so far as I am aware.

40 The terms "submerged mine" and "mine of the submerged class" are used throughout this specification and in the claims to identify the general type or class of mines to which the invention pertains, and of course 45 mean mines which, when placed for use, are to be submerged. They are to be read with this understanding.

Automobile or locomotive torpedoes are 50 not comprehended within the phrase "mine of the submerged class" or any similar language used in this description and claims.

I claim:

1. A mine of the submerged class containing within itself a source of electric energy, 55 a circuit including said source, a circuit closer, and heat-actuated means for completing the circuit through said closer; and means for exploding said mine adapted to be brought into action through the closure 60 of said circuit.

2. A submerged mine comprising a shell or 65 container; an explosive charge therein; detonating means for exploding said charge, including a movable firing-pin and electro-magnetic means for actuating said pin: a

source of electric energy; a circuit containing said source, the electromagnet of the detonating device, and a normally open circuit closer adapted to close on a rise of temperature; and a second electric circuit including a source of electric energy, an electric heater in proximity to the circuit-closer of the first-named circuit, and a normally open circuit-closer adapted to be brought into action through a sound-responsive device carried by the mine. 70

3. A mine of the submerged class, comprising a shell or container provided with a microphonic receiver, a source of electric energy, and a circuit including said source, the 80 receiver, and a make-and-break device actuated by the receiver and serving alternately to close and open said circuit; an explosive charge; a second circuit-closer responsive to and rendered operative by the action of the 85 receiver; a second source of electric energy; means for firing the explosive charge; and a circuit including said second source of energy, the second circuit-closer, and the means for firing the explosive charge, the movable 90 element of the second circuit-closer being adapted to return automatically to normal position if the sound-responsive device ceases to function before the second circuit is closed. 95

4. A mine of the submerged class, comprising a shell or container; an explosive charge within said container; a sound-responsive device carried by said shell or container; a source of electric energy; means actuated by the sound-responsive device, included in and serving alternately to make and break the circuit of the source of energy; an electrical device for firing the explosive charge; a source of electric energy 105 for actuating said firing device; and a circuit including said source of energy, the firing device, and a second circuit-closer, said second circuit-closer being under the control of and brought into action by the sound-responsive device and its circuit-closer if the action of the sound-responsive device 110 continue a sufficient length of time but resuming its normal condition or adjustment if the action of the sound-responsive device 115 cease before said circuit is completed.

5. A mine of the submerged class, comprising a shell or container; an explosive charge within said shell or container; a detonating device adapted to be brought into 120 action through a rise of temperature; a microphonic receiver responsive to sound-waves; and a heating device brought into action through vibration of the microphonic receiver incident to reception of sound-waves, and serving when so energized to bring into action the detonating device. 125

6. A mine of the submerged class containing within itself an explosive charge; electrical means for exploding said charge; a 130

- source of electric energy; a circuit including said source of energy, exploding device, and a thermostatic circuit-closer; an electric heater for said thermostatic circuit-closer; 5 and thus bringing into action said explosion producing device if the sound-responsive device continue in action a sufficient time, but to restore the circuit closer to normal position or adjustment if such action cease before completion of the circuit. 70
- 5 5 a source of electric energy; a microphonic receiver and a make-and-break device actuated thereby; and a circuit including said source of energy, receiver, make-and-break device, and heater. 11. A mine of the submerged class comprising within itself a destructive charge; a discharging device therefor; a sound-responsive device exposed to sound waves 75 proceeding through the medium in which the mine is located; and connections between the sound-responsive device and the discharging device, including a thermostatic circuit closer capable of being set to close the firing circuit only after a predetermined period of operation of the sound-responsive device. 80
- 10 7. A mine of the submerged class comprising as a unitary and self-contained structure, a shell or container; an explosive charge; a detonating device for firing said charge; and means responsive to sound-waves for bringing into action said detonating device, said means including a circuit-closer tending to close gradually the detonating circuit as the sound-responsive device continues to function but to resume its normal condition or adjustment if the sound-responsive device cease to function before the detonating circuit is completed. 12. In combination with and as parts of an explosive mine of the submerged class, 85 a discharging means therefor; a sound-responsive device; and means intermediate the sound-responsive device and the discharging means, and operable through continuing action of the sound-responsive device to complete in a predetermined period of time the connection between the sound-responsive means and the discharging means. 90
- 15 8. A mine of the submerged class comprising within itself and as a unitary structure, a shell or container; an explosive charge contained therein; an electric detonating device; a source of electric energy for said device; an electric circuit including said source, detonating device, and a 13. In combination with and as parts of gradually-acting circuit closer; a sound-responsive device; a source of energy therefor; a make-and-break device actuated by said sound-responsive device; and a circuit including the sound-responsive device, the 95 make-and-break device, and the circuit closer of the detonating circuit; whereby sound waves acting upon the sound-responsive device are caused in turn to move one element of the detonating circuit gradually 100 toward the companion element thereof and if the action of the sound-responsive device continue for a predetermined length of time, to complete the detonating circuit and fire the explosive charge. 14. In combination with an explosive mine of the submerged class and with a discharging device therefor, a sound-responsive device, and a timed connecting device interposed between the sound-responsive device and the discharging device; whereby the discharging device is brought into action by the action of the sound-responsive device continued for a predetermined period of time. 105
- 20 9. A mine of the submerged class comprising within itself and as a unitary structure, a shell or container; an explosive charge; a sound-responsive device; a source of electric energy; and a detonating device 15. A mine of the submerged class comprising within itself a destructive charge; a discharging device therefor; a sound-responsive device exposed to sound waves proceeding through the medium in which the mine is located; and connections between the sound-responsive device and the discharging device, including a thermostatic circuit closer capable of being set to close the firing circuit only after a predetermined minimum period of operation of the sound-responsive device. 115
- 25 10. A self-contained mine of the submerged class, comprising an explosive charge; electrical means for causing explosion of said charge; and means responsive to sound waves, serving to actuate a 16. In combination with an explosive mine of the submerged class, a sound-responsive device; an electric circuit; a mine-discharging device included in said circuit and operable through elevation of temperature; a circuit closer for completing the circuit of 120
- 30 35 40 45 50 55 60 65 70 75 80 85 90 95 100 105 110 115 120 125 130

means controlled by the sound-responsive device for actuating said circuit closer, and thereby effecting the requisite elevation of temperature.

5 17. In combination with an explosive mine and a discharging device therefor; a sound-responsive device; and a thermostatic device interposed between the discharging device and the sound-responsive device, and 10 operable by the latter to bring the discharging device into action.

18. In combination with an explosive mine, discharging means therefor; a sound-responsive device; and normally interrupted 15 connections between the sound-responsive device and the discharging means, including a gradually moving member under control of the sound-responsive device, for effect-

ing a gradual or timed completion of the connections between the sound-responsive device and the discharging means, and capable of adjustment to effect such closure upon the lapse of a predetermined period of time.

19. A submersible mine, comprising a 25 sound-responsive device; a firing device; and a circuit closer located between said sound-responsive device and said firing device, and serving to close the circuit upon the lapse of a predetermined period of time 30 beginning with the reception of sound waves by the sound-responsive device.

In testimony whereof I affix my signature.

JOHN J. DUFFIE.
